UNITED STATES PATENT OFFICE.

ALBERT PICK, OF CHICAGO, ILLINOIS.

DESIGN FOR A TUMBLER.

47,759.

Specification for Design.

Patented Aug. 24, 1915.

Application filed February 4, 1915. Serial No. 6,182. Term of patent 14 years.

To all whom it may concern:

Be it known that I, ALBERT PICK, a citizen of the United States, residing at Chicago, in the county of Cook and State of Illinois, have invented a new, original, and ornamental Design for Tumblers, of which the following is a specification, reference being had to the accompanying drawing, forming a part thereof.

In the drawings: Figure 1 is a side elevation of a tumbler showing my new design. Fig. 2 is a plan.

The tumbler is characterized in having a

slightly tapered inverted-conoidal body and lower portion *a*, which terminates and is curved inwardly slightly but somewhat abruptly at *b* and a cylindrical upper portion *c* above the curve *b*.

I claim:

The ornamental design for a tumbler as described and shown.

ALBERT PICK.
